BUMPER JACK

John Harwood, Jr., Ashland, Ohio, assignor to
The Simmons Manufacturing Company, Ash-
land, Ohio, a corporation of Ohio

Application March 12, 1938, Serial No. 195,439

2 Claims. (Cl. 254—93)

This invention relates to an improvement in jacks and aims to provide a very rugged jack having a limited number of durable parts arranged in a very compact form.

While the jack herein disclosed is adapted for many uses, it is particularly adapted for the use popularly known as a bumper jack. Modern automobiles are so constructed and arranged that it is difficult to place a jack directly under the axle or associated parts as was formerly done. The type of jack here disclosed is adapted to engage beneath a bumper bar or a projecting portion of the car frame at the front or rear of an automobile so as to lift one end or one corner of the frame as required to work on a wheel or axle.

An object of the present invention is to provide a jack of this type which is of the self-contained hydraulic type easily placed and manipulated by a person in standing position thus obviating awkward positions, soiled clothes and the usual discomforts of jack operation.

Another object of the present invention is to provide a powerful jack in a very compact form having a small number of parts easily manufactured and assembled so that the jack is simple, efficient, cheap to manufacture and takes very little storage space.

Other novel features of my improved jack and the details of structure by which I am enabled to provide all of the above described advantages are fully set forth in the accompanying specification and drawing and the essential features will be summarized in the claims.

In the drawing, Fig. 1 is an elevational view of my improved jack with certain alternative positions of the parts being shown in dot-dash lines; Fig. 2 is an enlarged longitudinal sectional view through the jack of Fig. 1; while Figs. 3 and 4 are transverse sectional views taken along similarly numbered lines of Fig. 2.

At the lower portion of the jack I provide lifting means including coacting cylinder and piston members, one of which is adapted to rest upon the ground or other supporting surface while the other member is arranged to move upwardly carrying a lifting hook or other attaching device and also supporting on its upper end a reservoir for the hydraulic fluid, suitable valve mechanism, pumping mechanism, etc. In the form shown the piston member 10 is oscillatably mounted on a pin 11 which is supported in a base or shoe 12. The coacting cylinder member is indicated at 13 and is sealed and guided at its lower end by a cap 14 which is in threaded engagement with the lower end of the cylinder and has a central open-

ing through which the piston passes. Packing material 15 provides a sealing means at this point. The piston 10 carries at its upper end a piston head 16 of leather or composition material 5 providing a substantially fluid-tight seal between the piston and the inner walls of the cylinder. Adjustably mounted on the cylinder 13 is the lifting hook 17 or other means for attaching the jack to the member to be moved. The lifting hook in the form shown has a split shank 18 embracing the cylinder 13 and clamped to the cylinder by a clamping screw 19 which may be manipulated by the handle 20. Various positions of the lifting hook are shown in dot-dash lines in Fig. 1.

Rigidly mounted on the upper end of cylinder 13 is a valve block 21 housing valves adapted to control the flow of fluid to and from the cylinder and piston lifting means 10—13. In threaded engagement with the upper end of the valve block 20 is a reservoir cylinder 22. The upper end of this structure is sealed by the threaded cap 23. Located centrally of the reservoir is the hydraulic power cylinder 24 which is suitably supported on the valve block as by the threaded connection shown. The hydraulic plunger 25 is reciprocable within cylinder 24 and carries a suitably sealed piston head 25a. The upper end of the plunger 25 passes through a suitable opening in the cap 23 and is sealed in its passage therethrough by the packing gland 26. To the upper end of the plunger 25 is secured a suitable operating member. In the present form this comprises a cap or knob 27 having a downwardly extending sleeve 28 connected therewith, this sleeve being reciprocable along the outer face of cylinder 22 and cap 23. For guiding this reciprocating movement of sleeve 28 and for limiting that movement in the upward direction an annular ring 29 has threaded engagement with the inner surface of sleeve 28 at its lower end and slidably engages the outer surface of reservoir cylinder 22.

The hydraulic pump 24—25 acts as a force pump to deliver fluid from reservoir 30 into the chamber 31 above the head of piston 10. To this end the valve block 21 at its upper end as shown in Fig. 3 is cut away at one side so as to provide an inlet passage 32 which is normally closed by the ball valve 33 spring pressed to closed position by the spring 34. This passageway communicates with the centrally located passageway 35 communicating between cylinder 24 and the chamber 31. This latter is the outlet passage for fluid pumped by plunger 25 to the chamber 31 and is normally closed by the ball valve 36 which is

pressed toward closed position by spring 37 which in turn is held in position by the hollow screw 38.

Within the valve block 21 I also provide means for bypassing the pump valves so as to permit the return of fluid from chamber 31 to reservoir 30 so that the jack will be lowered without other effort or manipulation on the part of the operator. To this end a small bypass is provided at 39 which communicates at its upper end with reservoir 30 and at its lower end with port 40 which communicates with passageway 35 below valve 36. This port is controlled by the needle valve 50 which is sealed in the valve body by a suitable packing gland 51 and controlled by the wing nut 52.

The operation of my jack is as follows: The shoe 12 is placed on the ground or floor beneath, for instance, the bumper bar of an automobile and the lifting hook 17 is raised into engagement with the bumper bar by adjusting its position as indicated in Fig. 1 and locking the lifting hook by the clamp screw 19. The plunger knob 27 is then grasped and plunger 25 is reciprocated to force liquid stored in reservoir 30 into chamber 31. It will be noted that the parts are sufficiently long and attenuated so that when jack operation starts the knob 27 is substantially waist-high to the operator to accomplish the before-mentioned object of providing a device easily manipulated by a person in standing position. On each up stroke of plunger 25 suction is created in cylinder 24, ball valve 33 opens and admits fluid from reservoir 30 to cylinder 24 and passageway 35. On the down stroke of the plunger, valve 33 closes and valve 36 opens, discharging the fluid under pressure into chamber 31 and the lifting cylinder 13 relative to piston 10 and the base 12, thus gradually the lifting hook 17 is raised to the desired height. To lower the load, port 40, which has been closed during the lifting operation, is opened by backing off the needle valve 50 which may be nicely controlled so as to permit fluid to return at the desired rate from

chamber 31 through passageway 35, port 40 and bypass 39 to reservoir 30. The load on hook 17 and cylinder 13 will thus descend as rapidly as permitted by the escape of fluid through the port 40 and the load will return to its lowermost position.

What I claim is:

1. A jack of the class described comprising a piston of small diameter having a piston rod connected with a base, a long attenuated cylindrical tube coacting with said piston to form an expandable chamber between them, a lifting member carried by said tube on its outer wall, a long tubular reservoir above said cylindrical tube, and 10 coaxial therewith, said reservoir being closed at the top by a wall, a valve block rigidly connected between said tube and said reservoir, a pump cylinder of smaller diameter than said reservoir and supported by said block axially of said reservoir, a pump plunger coacting with said cylinder and extending through the top wall of said reservoir, there being passageways in said block communicating between said reservoir and said pump and said chamber, an inlet valve permitting flow into said pump from said reservoir, an outlet valve permitting flow out of said pump into said chamber, there being means for returning fluid from said chamber to said reservoir to lower the jack, and the length of said tubular reservoir and of said cylindrical tube being such that the operating end of said plunger at the top of said reservoir is at least substantially waist-high to an operator.

2. A jack as in claim 1, wherein the end of said pump plunger above said reservoir is provided with an operating knob substantially of the diameter of said reservoir, a sleeve extends downwardly therefrom in sliding engagement with the outside of said reservoir, and the diameter of 35 said knob and sleeve is sufficiently small to be easily grasped in the hand of the operator.

JOHN HARWOOD, JR.
